UNITED STATES PATENT OFFICE

ANTON WAGENBACH, OF ELBERFELD, GERMANY

BENDING MACHINE

Application filed March 10, 1928, Serial No. 280,788, and in Germany September 24, 1927. Renewed February 21, 1933.

The invention concerns a bending arrangement for bending machines adapted to bend various forms, as particularly cross bows, oval and angular spiraloid curves, which are 5 employed in iron concrete.

The invention consists therein that a vertical shaft, penetrating through a horizontal frame plate, bears a driver and there above a bending arm seizable by means of the driver 10 and driven in the opposite direction by a return spring. The advantage consists therein, that the return movement of the bending arm results automatically and that the bending shaft is able to turn continuously in one 15 direction, without being forced for producing a new bend to be first slowly guided back again into its original position by a reversing gear. A further advantageous arrangement consists therein, that in the frame plate a 20 number of holes are so provided, that an abutment for loosening the driver from the bending arm can be fixed on various points. In this way it is possible to execute bendings about angles of variable measurements very 25 quickly and particularly exact.

The driver is further mounted on a circular bending disk, which likewise contains a number of holes, into which bending bolts or bending rollers can be inserted so that, when 30 dismounting the bending arm, also by means of this bending disc polygonal bendings of spiraloid or helicoidal shape can be produced. Further also the bending disc can be dismountable, so that by mounting a bending 35 roller upon the bending shaft and additional rollers upon the frame plate also greater curves in the manner of three-roller bending works can be produced.

A valuable feature consists at last in applying 40 an abutment ledge provided with holes, which extends from the bending shaft so that the iron rods to be bent can be fed forward up to an abutment and the length of any piece to be bent can be simply and exactly fixed.

The drawings show the invention in employment for bending cross bows for iron concrete.

Figure 1 is a frontal view,
50 Figure 2 is a plan view,

Figure 3 is a side view.

Through a horizontal frame plate 1 of the bending machine a hexagonal or octagonal mounting tap of a vertical shaft 2 extends, on which a bending disc 3 is so mounted as 55 to rotate with the shaft 2. A bending arm is held freely rotatable there above on the shaft, and is pulled by a return spring, designed as a screw spring 5, into the resting position the spring being attached to a pin 60 7 of the bending arm.

A driver 6 held by a pivot 6' upon the turning bending disc engages a rib 9 of the bending arm by its surface 6'' and takes along with it the bending arm 4 until the 65 drive 6 runs by its surface 6''' against a loosening abutment 8 and thereby is so tilted in counterclockwise direction that its surface 6'' disengages from said rib 9 and lets the arm 4 jerk back.

For quickly and exactly adjusting the desired bending points an abutment ledge 10 is provided, having holes 11 for inserting abutment bolts 12; for the first hook bending an end abutment 13 is provided. The bending takes place around a roller 14; arranged centrally on the shaft 2, by means of a bending roller 15 fixed on the bending arm 4. For holding the iron straight a clamping disc 16 on the abutment ledge 10 is provided.

When the bending arm 4 and the driver 6 are taken off and bolts are put into the holes 17 of the bending disc 3, it is possible to bend cornered curves of types similar to screws or spirals by uninterrupted rotation of the disc the wire running to the bending machine from a reel mounted besides the bending machine with a braking action serving for obtaining a sufficient wire tension. 90 Instead of a disc with holes a disc with radial slots can be arranged on the frame plate 1 by using the roller 14 as a driving roller and mounting two bearings with further rollers with vertical axis on the frame plate 1 by using the holes 18 for fastening said roller bearings. The starting apparatus is actuated by a foot lever 20, which for uninterrupted bending is locked by a locking eccentric 95 21.

The action in bending cross bows for concrete iron is the following; the iron rod to be bent is inserted between the roller 14 and the clamping disk 16 and pushed forward 5 against the abutment 13. The bending disc rotating in clockwise direction takes along with it the bending arm 4 by its driver 6 catching a downwardly directed rib 9 of said arm, till the driver runs against the loosening abutment 8 shown in Fig. 2 for example at a 180° position which means that by the roller 15 an end hook is bent, and the arm is returned by the spring 5. The rods are then reversed end to end before the bending 10 disc begins to take along with it the bending lever 4 for the second time, which in the same manner of insertion of the iron (as shown in the drawings) produces the second end hook bending by aid of the roller 15. Also the 15 third and the fourth bending are produced in the same manner, but for this case the loosening abutment 8 is brought into the 90° position, for bending these corners at 90°, in contradistinction to the end hooks bent 20 at 180°. The movements of the arm 4 are for each bending procedure marked by an arrow line.

By changing the abutment length and the turning direction all kinds of concrete iron 25 can be bent in uninterrupted operation.

Instead of the designed tension spring 5 a leaf spring or a spiral spring, enclosed in a turning case, can be used.

I claim:

35 1. A bending machine, comprising in combination a frame plate, a substantially vertical shaft extending upward through said frame plate, a freely rotatable bending arm on said shaft, a driver arranged on said 40 shaft above said frame and adapted to rotate said bending arm when said shaft is in rotation, means for automatically bringing said driver out of engagement with said arm, and means for withdrawing said arm into a resting 45 position when disengaged.

2. A bending machine, comprising in combination a frame plate, a substantially vertical shaft extending upward through said frame plate, a freely rotatable bending arm 50 on said shaft, a driver arranged on said shaft above said frame and adapted to rotate said bending arm when said shaft is in rotation, a pivot holding said driver on said shaft, an abutment adapted to be fastened to said 55 frame plate in the way of said driver so as to bring the latter out of engagement with said arm as soon as the driver runs against said abutment, and means for withdrawing said arm into a resting position when disengaged.

3. A bending machine, comprising in combination a frame plate, a substantially vertical shaft extending upward through said frame plate, a freely rotatable bending arm 60 on said shaft, a spring extended between said

arm and said frame plate so as to draw said arm into a resting position, a driver arranged on said shaft above said frame and adapted to rotate said bending arm oppositely to the pull of said spring, and means 70 for automatically bringing said driver out of engagement with said arm.

4. A bending machine comprising in combination a frame plate, a substantially vertical shaft extending upward through said frame plate, a freely rotatable bending arm on said shaft, a driver arranged on said shaft above said frame and adapted to rotate said bending arm when said shaft is in rotation, means for automatically bringing said 75 driver out of engagement with said arm and means for withdrawing said arm into a resting position when disengaged, a ledge provided with holes, extending from said shaft in one direction, means for fastening said 80 ledge to said frame plate, and abutments 85 adapted to be fastened in said holes of said ledge.

In witness whereof I affix my signature.
